UNITED STATES PATENT OFFICE

NOAH S. HARTER, OF WAUKEGAN, ILLINOIS, ASSIGNOR TO KING BOAT COMPANY, A COPARTNERSHIP CONSISTING OF NOAH S. HARTER, ERNEST H. HARPER, A. F. BEAUBIEN, HARRY CHAPMAN, AND WALTER BILHARS

AQUAPLANE

Application filed May 19, 1927. Serial No. 192,587.

This invention relates to improvements in aquaplanes, surf boards, rafts, and the like, and more particularly to a collapsible and foldable aquaplane, automatically inflatable, and adapted to travel with less water resistance and more stability than devices of this character heretofore known or now in use.

Previously known devices of the character of this invention have been bulky, difficult to carry or pack away, and, if inflatable, were only so by air from the lungs or by small pumps. Furthermore, the well known types of sea sleds are substantially flat, subject to an undesirable amount of water resistance when in use, and tend to bounce over the waves in rough manner instead of riding smoothly, whereby they may only be ridden with great difficulty or by an experienced rider.

With these objections in view, it is accordingly an object of this invention to provide an automatically inflatable aquaplane or the like.

Another object of this invention is to provide a collapsible and foldable aquaplane or the like, whereby the same may be adjusted to a compact form occupying a minimum space.

Another object of this invention is to provide a surf board or the like, constructed of extremely light material and easily transportable.

Still another object of this invention is to provide an adjustable aquaplane or the like adapted for use in either a flat or V-shaped form.

A further object of this invention is to provide a surf board or the like having substantially a V-shape, whereby the same is adapted to ride smoothly and with little water resistance.

A still further object of this invention is to provide a surf board or the like adapted to be adjusted to different angularities of cross-section while in use by the rider thereon.

Other and further important objects of this invention will be apparent from the disclosures in the specification and the accompanying drawings.

This invention (in a preferred form) is

illustrated in the drawings and hereinafter more fully described.

On the drawings:

Figure 1 is a top plan view of a device embodying principles of the present invention.

Figure 2 is an enlarged end view of the device taken from the right of Figure 1.

Figure 3 is an enlarged elevational view of a part of the device with a portion of the casing broken away.

Figure 4 is an enlarged vertical sectional view taken substantially along line IV—IV of Figure 3.

Figure 5 is an enlarged fragmentary bottom plan view of the device.

Figure 6 is a sectional view of a portion of the device.

As shown on the drawings:

In the illustrated embodiment of this invention there is shown an aquaplane or surf board 1, composed of a pair of collapsible members 2 and 3, substantially alike, secured together by the flexible hinges 4 thereby providing portions upwardly diverging from the center line of the device. Each of the members 2 and 3 is provided with a short angle iron 5 to which is secured a ring 6, and attached to the rings 6 are tow lines 7 and a hand line 8 for a rider to grasp and thereby steady himself.

On the bottom of the member 2 adjacent its inner edge there is secured a strip 9 of any desired strong, resilient material, and a similar strip 10 is secured in a similar manner to the member 3. These strips are perforated and provided with eyelets 11 to accommodate a lacing 12. As shown in Figure 2 when the device is ready for use the sides are in angular relation to each other and an inverted V notch is formed between them as shown at 13, the apex of the notch being adjacent the hinges 4. The angular relation between the members 2 and 3 may be varied at will by the user or rider of the device. If the rider stands with both feet adjacent the junction point of the members 2 and 3, the V notch 13 will be widened due to the rider's weight, the resilient strips 9 and 10 permitting this widening of the notch and the angular relation between

100

the members 2 and 3 will thereby become more acute. Conversely, if the rider stands with his feet adjacent the outer edges of the surf board, the notch 13 will be substantially closed and the angle outlined by the members 2 and 3 will become very obtuse or, if desired, may disappear entirely. Obviously, if so desired, the sea sled 1 may be used with both members in a perfectly flat condition.

10 Since the members 2 and 3 are alike in internal construction, for the purpose of brevity, only one will be described. The internal structure of each of these members is substantially the same as that disclosed in my co-pending application for "collapsible air chamber seat," filed May 19, 1927, Serial No. 192,586.

Section 3 (section 2 being identical thereto) comprises a top board 14 and a bottom board 15 in spaced relation thereto, around which boards and enclosing the same is a casting or covering 16 which is preferably of canvas so treated as to be waterproof. It is to be noted that the topboard 14 extends forwardly, at the front ends of the section 3, beyond the bottom board 15, and the covering 16 provides a substantially upwardly arced surface, which construction effectively prevents the sea sled from "digging into" the water when in use. As shown in Figure 3, the covering 16 provides side walls and end walls for an air chamber 17 between the top and bottom boards 14 and 15, respectively. To maintain the top and bottom boards in spaced relationship against pressure exerted thereon when the device is in use, a plurality of angularly bent supporting rods or braces 18 are provided within the casing between the top and bottom boards. These braces 18 have inwardly turned tips 19 pivotally engaged within straps 20 secured to the bottom board 15. In order that all of the brace rods 18 may be actuated uniformly and simultaneously, they are interconnected by a flexible strip 21. To limit the pivotal movement of the braces 18, one end of the connecting strip 21 is attached to a tension strip 22 which is secured to the bottom board 15 at 23. A pull cord 24 is attached to the tension strip 22 and a second pull cord 25 is attached to the opposite end of the connecting strip 21. These pull cords may be of any desired material but are preferably narrow strips of double-thickness or extra-heavy canvas. A pair 55 of apertures 26 are provided through the covering 16 and top board 14.

Within these apertures 26, each of which is adjacent either end of the section 3, there are provided flanges 27 which are adapted 60 for the insertion therein of stop plugs 28 and 29, respectively. Since the stop plugs 28 and 29 and their corresponding flanges 27 are identical, for the purpose of brevity, only stop plug 28 and one of the flanges 27 will be described herein. Flange 27 is re-

cessed as shown at 27^a and the bottom of the recess is provided with an inwardly extending portion 30 which in turn is provided with inwardly extending tongues 31 diametrically opposed to each other and of substantially one-fourth the circumference of an aperture 32 through the portion 30 of the flange.

70 The stop plug 28 comprises a metal disc 33 having integral upwardly projecting portions 34 thereon which portions are diametrically opposed to each other and provide gripping means for manipulating the plug. In juxtaposed relationship to the disc 33 there is provided a disc gasket 35, preferably of rubber, against the underside of which is secured a second metal disc 36 provided with 80 downwardly inclined portions 37 thereon of substantially one-fourth the circumference of the disc 36 in length and adapted to engage underneath the inwardly projecting portions 31 of the flange 27 to insure a watertight joint between the plug and flange. The pull cord 24 is attached to the under side of the stop plug 28 by the rivet 38 which also holds the various parts of the plug 28 together, and in similar manner the pull cord 25 is secured to the stop plug 29.

85 In the operation of the section 3, assuming it is desired to deflate or collapse the same from its inflated position shown in Figure 3, 90 stop plug 28 is removed and the pull cord 24 is given a slight tug or jerk thereby actuating all of the braces 18 which will pivot within the straps 20 and assume a horizontal position. Due to the weight of the top board 14, 100 flexible covering 16 will cave in at the sides and ends and the device will assume the compact form shown by the dotted lines in Figure 3, the air contained within the chamber 17 passing outwardly through the aperture 105 left by the removal of the plug 28. The pull cord 24 may then be pushed back in the chamber 17 and the stop plug 28 inserted in the flange 27.

110 To inflate the device from its compact form, stop plug 29 is removed and the pull cord 25 is actuated by a slight tug or jerk thereby elevating the brace rods 18 which simultaneously force the top board 14 upwardly. The air chamber 17 is automatically filled simultaneously with this operation by air passing through the opening left by the removal of the stop plug 29. It is to be noted that the brace rods when in their upright position are inclined slightly from the vertical towards the pull cord 25, further inclination of the rods being prevented by the tension strip 22. Due to the inclined position of the rods and this tension strip great pressure may be exerted on the top board 14 without causing the 120 device to collapse. After the device is in inflated position, as shown by the full lines in Figure 3, the pull cord 25 is pushed back into the chamber 17 and stop plug 29 is replaced thereby providing a water-tight inflated mem- 130

ber. The member 2, of course, is identical in structure and operation with the member 3.

In operating the device as a whole, assuming it is desired to fold the same into its compact form from its operative position shown in Figures 1 and 2, the members 2 and 3 are deflated as previously described, the lacing 12 is removed and member 2 thrown over on member 3 (or vice versa) and both members secured in this position by tying the lace 12 there-around. The device will now be in a flat compact form which is easily carried or packed away in a minimum space. When it is desired to again use the device, lacing 12 is untied, the device thrown open in the position shown in Figure 1, members 2 and 3 inflated, and the strips 9 and 10 are laced together as shown in Figure 5.

From the foregoing, it is apparent that I have provided an aquaplane of novel construction, with obvious utility and advantages over previously known devices of this character. The device described herein due to the angular relation between the sides will ride smoothly with little water resistance, and does not necessitate an experienced rider but permits a novice to enjoy the same. Moreover, the device disclosed herein is more stable than previously known devices of this character since the rider may elevate either foot or stand with both feet on one half of the device without overturning the same. Further, the device is of few parts and simple construction, very durable, and economical to manufacture.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. An aquaplane comprising a plurality of members hinged together on one side, and resiliently secured together on the opposite side.

2. In a device of the class described, a pair of angularly related members hingedly secured together on one side, and resilient means holding said members together on the other side, said means permitting variations in the angular relation between said members.

3. In an aquaplane, a pair of members, flexible hinges securing said members together on one side, a strip on the opposite side of each of said members, and lacing engaging said strips.

4. In a surf board, a pair of collapsible members angularly related to each other, said members hinged together on one side and resiliently secured together on the other side, each of said members comprising a top board, a bottom board, and pivoted supporting means therebetween.

5. In an aquaplane, a pair of collapsible members hinged together, each of said members comprising a flexible casing, a pair of juxtaposed members within said casing, a plurality of pivoted supports between said second mentioned members, and means for actuating said supports simultaneously. 70

6. In a device of the class described, a pair of angularly related members secured together, each of said members comprising a water-proof casing, a pair of spaced boards therein, a plurality of pivotally mounted braces between said boards and secured to one of said boards, a strip interconnecting said braces, means for limiting the pivotal movement of said braces, a pull cord connected to said means, and a pull cord connected to said interconnecting strip. 75

7. In a device of the class described, a pair of members secured together, said members being foldable upon each other, each of said members comprising a casing having an air chamber therein, a top board, a bottom board, braces between said boards, and means for simultaneously actuating said braces, said chambers being automatically inflated or deflated concurrently with the actuation of said braces. 80

8. In an aquaplane or the like, a pair of collapsible air chamber members hingedly and resiliently secured together, each of said members having a pair of apertures therein and comprising a casing, a pair of juxtaposed members therein, interconnected braces pivotally mounted between said juxtaposed members, means for limiting the pivotal movement of said braces, stop plugs removably engaged in said apertures, and a pair of pull cords for actuating said braces. 95

9. In a device of the class described, a plurality of members adjustably secured together, each of said members comprising a casing, a top board, a bottom board, and supporting means within said casing, said top board extending forwardly beyond said bottom board to permit said casing to arc upwardly. 100

10. In a device of the character described, a pair of collapsible angularly related elements, each of said elements including a top member, a bottom member, and means disposed between said members movable in one direction for expanding said element and in the other direction for collapsing said element. 115

11. In a device of the character described, a pair of collapsible members flexibly connected, means within each of said members for expanding the same, and means for actuating said first mentioned means, said members being automatically filled with air simultaneously with the actuation of said second mentioned means. 120

12. In a device of the character described, a pair of collapsible members flexibly con- 130

nected, each of said members including a casing, means within said casing for holding the same expanded, and means for actuating said first mentioned means to collapse said casing, said second mentioned means permitting the automatic expulsion of air from said casing simultaneously with the collapsing thereof.

13. In a device of the class described, a plurality of angularly related collapsible members, resilient means for connecting said members, said means permitting the angular relation between said members to be varied.

14. As an article of manufacture, an aquaplane including a plurality of members, and means connecting said members in upwardly diverging relationship.

15. As an article of manufacture, an aquaplane including a plurality of members, means connecting said members in angular relationship, said means permitting said relationship to be varied at will by pressure properly applied to the top of said aquaplane.

16. As an article of manufacture, an aquaplane including a pair of collapsible buoyant members, said members being foldable one upon the other when collapsed, and means for resiliently connecting said members in angular relationship when said aquaplane is adjusted for use.

17. As an article of manufacture, an aquaplane having a center line and equal portions upwardly diverging therefrom to aid in balancing said aquaplane.

35 In testimony whereof I have hereunto subscribed my name at Waukegan, Lake County, Ill.

NOAH S. HARTER.
